UNITED STATES PATENT OFFICE.

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY.

BUTT FOR SAND RAMMERS.

1,415,905.

Specification of Letters Patent. Patented May 16, 1922.

Application filed August 2, 1920. Serial No. 400,599.

To all whom it may concern:

Be it known that I, EDWARD W. STEVENS, a citizen of the United States, residing at Detroit, in the county of Wayne and State of Michigan, have invented certain new and useful Improvements in Butts for Sand Rammers, of which the following is a specification.

My invention relates to improvements in rammers such as sand rammers and has more particular relation to the butt of such tool and method of making the same. The object thereof is to provide a butt of simple and light construction and one which is moreover very efficient and durable considering the character of the work done.

In the drawings Fig. 1 is an elevation of a sand rammer butt embodying my invention; Fig. 2 a section on the line 2—2 of Fig. 1; Fig. 3 a view illustrating the mode of operation of producing the butt; Fig. 4 a plan view of the die; and Fig. 5 a plan view of the metal disk in its original shape as used in the die.

Referring to the present embodiment of my invention as herein shown the butt comprises a body portion 1 which in practice is made very light and consequently I prefer to employ aluminum as the material and make the same hollow thereby providing a large central chamber 2. This body is cylindrical at its lower or outer end and is truncated conical at its upper end with the result that there is no chance of lodgment of sand upon any portion thereof which would be liable to be thrown back in the face of the operator during the ramming operation.

Inasmuch as a light material such as aluminum is comparatively soft and not sufficiently durable to withstand the impact of the butt against sand, etc., I provide the body with an end cap of hard material such as thin sheet steel which is applied thereto in the following novel manner.

The extreme lower or outer end of the butt is slightly reduced in diameter as compared with the main body of the butt as indicated at 3, the difference equaling the thickness of the sheet metal plate or disk 4 which is applied thereto. Between these two diameters of the butt there is provided a circumferen-

tial groove 5 adapted to receive the flange 6 of the disk in the manner now to be explained.

In practice the disk 4 with its upstanding marginal flange 6 is applied to the butt in a single operation through the medium of the die 7. As shown in Fig. 3 the disk is laid in the die with its margin resting upon the shoulder 8 of such die. The butt which is secured to any suitable pressure means as a power press is forced directly downwardly with the result that the disk 4 is turned and wrapped around the corners of the butt and the flange 6 is forced into the groove 5. It will be understood that the die is provided with a circular socket 9 into which the disk and the lower end of the butt is forced in this operation.

According to this construction the butt is made very light and is provided with a durable end or cap and moreover such cap is so applied thereto as to become practically an integral part of the butt. Moreover the steel cap when worn out can be readily replaced thereby prolonging the life of the butt.

I claim:

1. A sand rammer butt comprising a body made of a light soft material and a separate end made of sheet metal.

2. A sand rammer butt comprising a body made of aluminum and a separate end of sheet metal secured to such body.

3. A sand rammer butt comprising a hollow body of aluminum having a circumferential groove near its outer end, and a separate end of sheet metal having an inwardly directed flange received by said groove.

4. A sand rammer butt comprising a body which is cylindrical at its outer end and truncated conical at its inner end, and a sheet metal end applied to the cylindrical outer end of such body.

5. A sand rammer butt comprising a body which is cylindrical with its extreme outer end reduced slightly in diameter and which has a circumferential groove at the junction of the two diameters, and a disk of sheet metal applied to the end of such body and the reduced diameter thereof, said disk having a marginal flange received by said groove.

EDWARD W. STEVENS.
